JOHN E. COVEY, OF CHICAGO, ILLINOIS, ASSIGNOR TO SWIFT AND COMPANY, OF CHICAGO, ILLINOIS, A CORPORATION OF ILLINOIS

BACON HANGER

Application filed October 5, 1931. Serial No. 566,953.

The invention relates to a bacon hanger. The invention also relates to the employment of the particular bacon hanger or skewer type of hanger, as it is sometimes called, in an assemblage which comprises a slab of bacon during the preparing and treatment of the bacon slabs as is customary or as is done in the meat packing industry.

The present invention is designed for the production of skinned bacon. The conventional bacon of commerce is produced by curing and smoking that portion of the hog carcass known as the belly, two sides of bacon being produced from each hog.

Bacon is marketed either in the slab or slice form. Much of the bacon produced in a packing house is sliced and packed in the packing house, being shipped by the packing house in large quantities to consumers or retailers.

Sliced bacon must be produced in condition for immediate use without further treating by the consumer, and inasmuch as the skin or rind of the bacon is inedible by reason of its toughness, it must be removed before the bacon is sliced.

Usually the bellies are skinned before curing in order that use may be made of the skin, but it may be removed either before or after smoking. In conventional packing house practice, whether or not the skin is removed, a comb hanger or toothed instrument is attached to one end of the product by inserting the nail-like teeth of the hanger entirely through the product, the product then being suspended in smoke by the hanger, as it is necessary that the product be well secured in order to withstand the ordinary handling in processing. Such insertion of the teeth in a comb hanger entirely through one end of the belly results in unsightly holes which cause the grading down and sometimes utter loss of perhaps one pound on each belly.

In ordinary commercial practice, large scale retailers of bacon purchase skinned bellies in the slab from the packer and regularly return and receive credit for the end through which the teeth have been inserted. Such returned product must be disposed of by the packer at a greatly reduced price. This is a

considerable item, as a large quantity of bacon is sliced at the packing house or by large-scale retailers.

The present invention avoids such unsightly holes in the product, and, in its preferred form as practiced in connection with skinned bellies, contemplates the removal of all of the skin with the exception of a strip about one inch wide at one end of the belly to be engaged by the bacon hanger, whereby the slab may be suspended in the smoke house or stored without in any way damaging the product which is later to be sliced.

With the above and other objects in view, the invention consists in the construction and novel combination and arrangement of parts hereinafter described, illustrated in the accompanying drawing, and set forth in the claims hereto appended, it being understood that various changes in the form, proportion and minor details of construction, within the scope of the claims, may be resorted to without departing from the spirit of the invention or sacrificing any of the advantages thereof.

In the drawing:

Figure 1 is a perspective view of a bacon hanger shown applied to a slab of bacon and viewed from the skinned side thereof.

Fig. 2 is a similar view, viewed from the lean side of the slab.

Referring to the drawing, in which is illustrated the preferred embodiment of the invention, 1 designates a belly or bacon slab having all of the skin removed with the exception of a narrow strip 2 about one inch wide extending across the slab 1 at one end thereof. The narrow strip 2 is slit at intervals to form narrow, ribbon-like cuts 3 to permit a skewer 4 of a hanger 5 to be laced through the said narrow strip 2. The cuts 3 are preferably located adjacent to the ends of the strip and in pairs at intervals to provide narrow, vertically disposed, partially severed portions 6 beneath which the skewer 4 is passed, so that the major portion of the skewer will lie exteriorly of the narrow strip of skin and a minimum portion of the skewer will be permitted to come in contact with the edible portion of the slab.

The hanger 5 and the skewer 4, which constitutes the bottom supporting portion of the hanger, are formed from a single piece of stout wire or other suitable material 5 which is doubled and bent intermediate of its ends to form a supporting hook 7 composed of two sides which are twisted together at the shank portion 8 of the supporting hook. The wire is extended outwardly and 10 downwardly from the lower end of the shank 8 to form supporting arms 9 and 10, and the lower terminal portion of the hanger arm 9 is bent into approximately U-shape to form a keeper 11 for the safety-pin hanger. The 15 wire, which is resilient, is partially coiled or bent at the lower or outer end of the other hanger arm 10 to form a spring loop 12 and is then extended across the bottom of the hanger to provide the said skewer member 20 4. The skewer member or pin portion of the safety pin hanger has its free terminal portion 13 pointed to enable it to be readily passed through the hard portion of the fatty tissue in rear of or beneath the narrow strip 25 2 of skin, and the resiliency of the spring loop 12 of the hanger maintains the pointed terminal portion in engagement with the keeper 11.

The skewer of the safety-pin hanger is 30 straight and provides a form for maintaining the slab flat or straight while the bacon is being cured, and the belly or slab is maintained firmly against the straight skewer or pin member 4 by means of a wire 14 which 35 constitutes a confining member. The wire 14 passes around the lean side of the bacon and across the end edges of the same and has its terminal portion 15 coiled around the hanger arms within the keeper 11 and the spring loop 12. The wire 14 is waved or 40 sigmoidally bent between the side edges of the bacon, as indicated at 16, to enable the wire to exert the desired pressure on the slab of bacon at the lean side thereof without 45 danger of cutting into the bacon, and to reduce unsmoked area which would result from a wire in contact with the bacon throughout the length of the wire. The slab or belly of bacon is firmly maintained in a straight or 50 flat condition between the wire 14 and the skewer member of the hanger, and is thereby effectually prevented from curling while being processed. It will thus be seen that the device of the present invention enables 55 the bacon to be suspended and cured without danger of injury to the end of the slab by piercing holes therethrough.

The labor incident to severing the strip of skin 2 from the slab of bacon is very small, 60 and this strip of skin may of course be removed when the bacon is sliced. Any suitable means may, of course, be employed for making the cuts 3 in the narrow strip 2.

The safety-pin skewer hanger, while designed especially for skinned slabs of bacon

having the narrow strip 2 of skin at one end, may of course be employed for hanging unskinned slabs of bacon having the slits 3 arranged at one end of the slab in the position illustrated in Fig. 1 of the drawing. 70

From the foregoing and particularly in connection with the drawing it will be manifest that the hanger herein described is of the skewer type and that the skewer or pin member 4 thereof is threaded under narrow 75 transversely spaced loop providing portions of the skin or hide at the upper portion of a bacon slab during the normal support of the slab by the hanger. It will also be noted that the hanger shown may be considered as 80 having a central supporting section or hook provided by the hook 7 from which there depends outwardly extending spaced supporting arms 9 and 10 and that the skewer or pin member 4 is carried by and in fact is integrally connected to the lower end of the hanger or supporting arm 10 through the medium of the looped portion 12 that extends outwardly from the lower end of the arm 10 and which provides means whereby 85 the pin member is swingably supported by and from the lower end of the supporting arm 10. It will also be observed that the lower end of the other hanger or supporting arm, to wit, the lower end of arm 9 is re- 90 versely bent so as to provide a hook, eye or keeper portion at 11 into which the free end of the skewer or pin member 4 is positioned and by which the free end of the skewer or pin member is supported when in use. It 95 will also be noted that the confining member provided by wire 14 is in fact a U-shaped retaining member the back or transversely extending section of which provides a rear 100 transversely extending retaining bar 16 which is vertically waved so as to provide an increase in the pressing or retaining surface thereof over and above a straight bar, but according to certain aspects of the invention 105 this bar 16 could be either straight or waved. It will also be seen that from each end of this rear transversely extending retaining bar or retaining section 16 there forwardly extends spacing elements or legs the forward 110 end of each of which spacing elements is coiled at 15 about and secured to the lower end of the supporting arm or hanger arm. One of the coiled portions 15 is located within the area defined by the spring or coiled 115 loop 12 previously mentioned, while the other coiled portion 15 is located within the region of the hook, eye or keeper portion 11 previously referred to. The result of this construction is that the confining or retaining member provided by wire 14 is practically positioned at all times properly in a vertical direction in respect to the skewer or pin member, with the result that when the hanger is 120 in place for retaining a strip of bacon there is provided a bacon slab and hanger assem- 125 130

blage according to which the bacon slab is supported by the hanger so as to depend from the hanger and so that during such period the bacon slab is firmly clamped and positioned between the skewer or pin member 4 on the one hand and the retaining bar 16 of the confining member on the other. This confining of the upper end of the slab serves to maintain the slab in straight and proper condition and form during any treatment, processing, curing or handling of the bacon and the assemblage of which the bacon constitutes a part. Should the assemblage construction be one in which the bacon slab has 15 been dehided except for a narrow strip of hide or rind left at the upper end of the slab, then and in that instance it will be noted that the retaining member serves to maintain the skewer member and, through the skewer member, the hide in close relationship in respect to the rest of the meat of the slab, with the result that there is no tendency for the remaining portion of the skin or rind to be forcibly torn from the rest of the slab. In 20 other words, this clamping arrangement existing between the skewer hanger and the retaining member serves not merely to retain the upper end of the bacon slab in proper form but it also avoids completely dehiding the bacon slab which might otherwise result from rough handling if the clamping of the skin in place were not availed of.

What is claimed is:

1. A safety-pin type of skewer hanger for bacon slabs which hanger comprises a supporting member providing a hook at the upper portion thereof from which there depend spreading supporting arms, from the lower end of one of which supporting arms 40 through the medium of a loop section there is integrally connected and carried a swingable skewer or pin member, the other supporting arm being provided at the lower end thereof with a reversely bent section providing a U-shaped hook for the reception of the free end of the skewer or pin member, said hanger also comprising a U-shaped confining member which has a transversely extending retaining bar from which there forwardly extend spacing elements or legs the forward end of each of which legs is connected to the lower ends of the respective supporting arms 45 by being looped around the same, the looped portion of one of said legs being connected to the loop provided between the supporting arm and the skewer section or pin whereby the confining member is necessarily properly positioned against undue vertical movement relative to the skewer or pin member.
2. A safety-pin type of skewer hanger for bacon slabs which hanger comprises a supporting member providing a hook at the upper portion thereof from which there depend spreading supporting arms, from the lower end of one of which supporting arms through

the medium of an outwardly extending loop section thereof there is integrally connected and carried a swingable skewer or pin member, the other supporting arm being provided at the lower end thereof with a reversely bent section providing a hook or eye for the reception of the free end of the skewer or pin member, said hanger also comprising a confining member provided by a U-shaped member which is vertically waved in a back or retaining bar section thereof and which U-shaped member has at each end thereof a forwardly extending spacing or leg section, the forward end of each of which spacing sections is connected to the lower ends of the respective supporting arms by being looped around the same, the looped portion of one of said legs being located within the loop providing the integral connection between the supporting arm and the skewer or pin member whereby the confining member is necessarily properly positioned against undue vertical movement relative to the skewer or pin member.

3. A safety-pin type of skewer hanger 90 which comprises a supporting member having depending spreading supporting arms from the lower end of one of which supporting arms there is connected and carried a swingable skewer or pin member, the other supporting arm being provided at the lower end thereof with a reversely bent section providing a U-shaped hook for the reception of the free end of the skewer or pin member, said hanger also comprising a U-shaped confining member which has a transversely extending retaining bar from which there forwardly extend spacing elements or legs the forward end of each of which legs is connected to the lower ends of the respective supporting arms whereby the confining member is vertically positioned in cooperative relationship in respect to the skewer or pin member.

4. In the treatment of bacon slabs the assemblage which comprises a bacon slab dehided except for a narrow transversely extending strip left remaining at the upper end of the slab, the central transversely extending section of which remaining strip is vertically slitted so as to leave narrow loop providing sections, the ends of which loop providing sections are integral with the hide of the upper and lower portions of the strip, and a safety-pin skewer hanger comprising a supporting hook from which there extend depending spreading supporting arms, by one of which supporting arms a skewer or pin member is carried at the lower end thereof and relative to which said skewer or pin member is mounted so as to permit swinging movement of the skewer or pin member, the other of which supporting arms has at the lower end thereof a U-shaped open top hook for the reception and support of the free end of the swinging skewer or pin member, and

which hanger also has a retaining member providing a rear transversely extending retaining bar from the ends of which bar there forwardly extend spacing elements the forward ends of which are connected to the lower portions of the supporting arms, which hanger is adapted to be brought in the assemblage by introducing the skewer or pin member under the loops in such a manner that the major portion of the skewer or pin member rests against the outside of the skin in the region at the sides of said loop providing portions, the legs or spacing elements of the U-shaped retaining member being of such length that when the skewer is thus threaded under the loops and when the free end of the skewer is supported in the eye provided at the lower end of the supporting arm corresponding thereto said U-shaped retaining member serves to hold and clamp the upper end of the bacon slab firmly between it on the one hand and the skewer or pin member on the other whereby the upper end of the bacon will remain in proper form during the handling and treatment of the slab of the assemblage.

5. In the treatment of bacon slabs the assemblage which comprises a hanger and a bacon slab carried thereby, which bacon slab 30 has a hide portion left thereupon, which hide portion has a transversely extending section that is vertically slitted so as to leave narrow loop providing sections, the ends of which loop providing sections are integral with the hide above and below the slits, the hanger being of safety-pin skewer type and comprising a supporting section, depending outwardly spreading supporting arms extending from said supporting section, a relatively 40 straight skewer or pin member swingably mounted upon and carried at the lower end of one of said arms, the other of which supporting arms has a U-shaped eye for the reception and support of the free end of the skewer or pin member, and a U-shaped retaining member providing a rear transversely extending retaining bar from which retaining bar there forwardly extend leg or spacing elements the forward ends of 50 which are connected to the lower portions of the supporting arms, and which hanger in the assemblage is arranged in respect to the bacon slab in such a manner that the skewer or pin member is threaded under the loop providing sections and in such a manner that

the major portion of the skewer or pin member rests against the outside of the skin in the region at the sides of said loop providing portions, the legs or spacing elements of the U-shaped retaining member being of such length that when the skewer is thus threaded under the loops and when the free end of the skewer is supported in the eye provided at the lower end of the supporting arm corresponding thereto said U-shaped retaining member serves to hold and clamp the upper end of the bacon slab firmly between it on the one hand and the skewer or pin member on the other whereby the upper end of the bacon will remain straight during handling and treatment.

6. In the preparing and treatment of bacon slabs the assemblage which comprises a slab of bacon and a safety-pin type of skewer hanger; which slab of bacon has left thereupon at least a portion of the hide or rind, which hide is provided near the upper end of the slab with a transversely extending set of vertically extending horizontally spaced slits that leave a row of ribbon-like loop providing hide portions, the ends of which loops are integral with the skin above and below the slits; a safety-pin type of hanger providing a supporting section having horizontally spaced depending supporting arms, a skewer member or pin integral with the lower end of one of said depending supporting arms, and a U-shaped retaining member, said skewer or pin member being swingably mounted at the lower ends of one of said arms and supported at the free end in a hook provided at the lower end of the other supporting arm; said skewer or pin member being threaded under the loop providing hide portions but positioned so that except for said loop portions the skewer or pin member engages the outer side of the hide sections at each side of the loop portions; the U-shaped retaining member being shaped so that when the free end of the skewer or pin member is in the hook at the lower end of the supporting arm corresponding thereto the upper end of the slab is clamped between the skewer or pin member on the one hand and the U-shaped retaining member on the other.

Signed at Chicago, in the county of Cook and State of Illinois, this 28th day of September, 1931.

JOHN E. COVEY. 120
